CLAIM

The ornamental design for an ADJUSTABLE MEASURING SPOON as shown and described.

DESCRIPTION

FIG. 1 is a top perspective view of an Adjustable Measuring Spoon showing my new design;

FIG. 2 is a rotated top perspective view of the Adjustable Measuring Spoon of FIG. 1;

FIG. 3 is a bottom perspective view of the Adjustable Measuring Spoon of FIG. 1;

FIG. 4 is a rotated bottom perspective view of the Adjustable Measuring Spoon of FIG. 1;

FIG. 5 is a first side view of the Adjustable Measuring Spoon of FIG. 1;

FIG. 6 is a second side view of the Adjustable Measuring Spoon of FIG. 1;

FIG. 7 is a third side view of the Adjustable Measuring Spoon of FIG. 1;

FIG. 8 is a fourth side view of the Adjustable Measuring Spoon of FIG. 1;

FIG. 9 is a top plan view of the Adjustable Measuring Spoon of FIG. 1;

FIG. 10 is a bottom plan view of the Adjustable Measuring Spoon of FIG. 1;

FIG. 11 is a side view of the Adjustable Measuring Spoon adjusted to a first volume;

FIG. 12 is a side view of the Adjustable Measuring Spoon adjusted to a second volume; and

FIG. 13 is a side view of the Adjustable Measuring Spoon adjusted to a third volume.
